ROTARY PUMP

Filed Nov. 21, 1927

H. O. JACKSON
INVENTOR.
BY Fred H. Hayn.
ATTORNEY.

UNITED STATES PATENT OFFICE

HENRY ORR JACKSON, OF LOS ANGELES, CALIFORNIA

ROTARY PUMP

Application filed November 21, 1927. Serial No. 234,771.

My invention relates to pumps of the rotary type adapted to pump fluids, the known pumps of this type having but a comparatively low volumetric efficiency, said invention, however, comprising a marked improvement upon all existing pumps of this character.

It accordingly is an object of my invention to provide a novel form of rotary pump in which a casing equipped with inlet and discharge ports has positioned therein a liner, keyed thereto, which key is preferably positioned between said ports so as to form also an effective fluid seal therebetween, said liner being also eccentrically bored, to house a rotor which has a true circular motion, said rotor being concentrically positioned with respect to the outer periphery of said casing, a set of fluid pressure buckets being pivoted to said 15 rotor, which buckets are adapted to be actuated by centrifugal force as said rotor is rotated so that each of said buckets will create a suction on the inlet side thereof, and on the other push the fluid pumped to said discharge 20 port.

It is also within the province of my invention to provide my novel form of liner with inlet and exhaust ports positioned in staggered relation to prevent undue wear upon 25 the buckets and on the rotor, a shearing effect being produced on the fluid, and thus preventing swirling thereof, and hence insuring an even wear on said buckets and rotor.

It is moreover within the province of my 35 invention to use stationary pins, firmly fastened to the rotor, on which the buckets are pivoted; and when a long rotor is used, there may be a tendency to spring said pins. To 40 prevent this tendency I may employ a means in the shape of a plate, secured at one end to the rotor and at the other to the pin, thus insuring that the buckets will always be in true, and no uneven wear thereon or on the 45 rotor results. The use of said plates is optional.

Further objects and advantages of my invention as will hereinafter more fully appear, I attain by the construction and mechanism 50 described in the specification and illustrated

on the drawings, forming a part of my application.

Reference is had to the accompanying drawings, in which similar reference characters denote similar parts. In the drawings, 55

Fig. 1 is a side elevational view of my improved pump,

Fig. 2 is a cross-sectional view, taken on the line 2—2, Fig. 1, looking in the direction of 60 the arrows,

Fig. 3 is a similar view, taken on the line 3—3, Fig. 2, also looking in the direction of the arrows,

Fig. 4 is a detail perspective view of one of 65 the buckets,

Fig. 5 is a fragmentary elevational view showing a slight modification in which a means is provided for preventing the stationary pins from springing, and hence always hold the buckets in true. 70

Fig. 6 is an enlarged cross-sectional view, taken on the line 6—6, Fig. 5, looking in the direction of the arrows,

Describing my invention more in detail, my 75 novel form of pump has been subjected to a number of tests, which tests indicate 20 inches dry vacuum, and 28 inches with water seal, when used to pump water. The volumetric efficiency was better than 95% between 10 pounds and 40 pounds pressure, indicating a 80 marked improvement over existing and known pumps of this type.

As seen in the drawings, a preferably cylindrical casing 2, provided with the usual cylinder heads 4 and detachable bolts 6, has extended therethrough a shaft 8 adapted to be rotated within the bearings 10 equipped with the usual lubricating means and packing glands, shown but forming no part of my invention. 85

The casing 2 is provided with a suction inlet 12 and a discharge or exhaust outlet 14, to which may be screwed or otherwise secured, the usual suction and discharge pipes for the pump, a suitable base 16 being provided, 90 whereby said pump may be positioned or secured in any desired position.

The casing 2 is bored concentrically for the 95 reception of the liner 18, which liner is bored eccentrically, as shown in Fig. 2, for the re- 100

ception of the rotor 20 mounted on the shaft 8, and detachably associated therewith by the differently positioned locking keys or pins 22, which keys are so positioned so as not to weaken said shaft.

As seen in Figs. 2 and 3, the liner 18 has a thickened portion 24, which portion is cut away as at 26 to provide an exhaust or discharge passage leading to the discharge 14 of the pump, a set of discharge passages 28 being provided in said liner, which passages lead to the fluid pressure chamber 30 formed by the rotor 20 and said liner, which liner is also cut away as at 32 to provide an inlet or suction passage leading to the inlet 12 of the pump. A set of inlet passages 34 are also provided in the liner 18, and said passages, as well as the passages 28, are in staggered relation (see Fig. 1) so as to produce an even wear on the buckets 35, presently to be more particularly described, and also on the liner 18. As will be clear, as said buckets pass over said passages, there is a shearing effect on the fluid, thus preventing swirling, thereof and hence insuring an even wear on said buckets.

As seen in Fig. 2, a suitable key 38 is provided for locking the liner 18 to the casing, which key permits the ready removal of said liner from the casing, and, since said key is positioned both in said liner and said casing, and extends the entire longitudinal length thereof, it at the same time provides an effective seal between the fluid inlet and the discharge of the pump.

As seen more particularly in Fig. 2, the rotor 20 is provided with a set of pockets or cavities 40 of suitable form to receive the buckets 35, which pockets are shaped to conform to the shape of said buckets, said pockets opening laterally so that the buckets may be inserted in and removed from said pockets without removing the rotor 20, a rotor lip portion 37 being provided for a purpose presently to be explained.

The buckets 35 are constructed of suitable material and are preferably shaped as shown, each being provided with a body portion 42 cut away as shown so that it may be pushed laterally into the rotor, and a pivot portion 44, which portion has a cavity 46 to receive the stationary pivot pin 48, forced into a passageway 36 in the rotor 20, which pin preferably extends entirely through the rotor 20, as seen in Fig. 3.

The fluid pressure active portion of the bucket 35 comprises a blade or spoon portion 50, and is so positioned in the rotor that its radius swings close to but does not touch the complementary radius of the rotor pocket 40, and the opening or gap in the rotor, leading to the pockets or cavities 40, is sufficiently wide to let said blade or spoon portion pass freely therethrough, thus permitting the buckets 35 to fly out by centrifugal force as the rotor 20 is rotated, said buckets being free

to move in and out of the rotor without friction or back pressure, said buckets being obviously not subject to any wear in said movement. It will also be noted that the pivot pins 48 receive all stresses to which the buckets may be subjected, and otherwise there is no friction, whatever, between the buckets and the rotor, as just stated, a film of fluid being always maintained between the outer ends of the buckets, and the liner, and also between the radius of each bucket and the corresponding radius of the rotor pocket, and thus insuring a marked efficiency.

To compensate for any wear, a pair of plates 52 are provided, which plates may be reversed and replaced from time to time, and also permit the ready assembly of the pump, permitting the buckets 35 to be withdrawn laterally, without removing the rotor 20, for repair or replacement.

As seen in Fig. 2, the full diameter of the rotor 20 when in motion is in fluid seal with the tangent point of the center line of the liner 18, and to insure an effective fluid seal between the inlet and discharge ports, the buckets 35 (which may be of any preferred number) are so positioned in the rotor that the preceding bucket will not pass the intake port until the next succeeding bucket has passed the outlet port, the rotor with its lip portions 37 in the meantime forming an effective fluid seal with the liner 18 so that no fluid can possibly pass from the outlet to the inlet, thus providing for a marked efficiency of operation.

The next preceding bucket of the rotor 20 covers the last passages in the liner 18, up to within a short distance from the first discharge port in said liner, creating a partial vacuum or suction, when the next succeeding bucket passes the intake port.

Each bucket accordingly sucks in the fluid by the vacuum or suction created on one side, while the bucket on the other side pushes the fluid in front to the discharge or outlet of the pump.

In testing small pumps with a cylinder diameter of 3 inches and length of 1½ inches, running at 800 R. P. M., the centrifugal force on the buckets held the same to the liner wall at a pressure of 150 pounds. This conclusively proves that a larger pump, with longer and heavier buckets would produce a pressure of 500 or more pounds, if required.

It will be observed also that there is a true circular motion of the rotor and buckets at all times, there being no rubbing or braking effect, providing long life and marked efficiency for the apparatus, which is adaptable for use with any fluid, as desired. Moreover, the apparatus is simple in construction, easily and inexpensively manufactured, and easy to assemble and disassemble, providing a means for easy and quick repair.

In Figs. 5 and 6 I have shown a slight modi-

ification which is especially adapted for long rotors, and may be used or not, as desired. In such rotors there is a tendency for the stationary pins 36', driven in the rotor, to spring. To counteract this tendency, I may provide cheek or side plates or other holding members 54', through which said pins are passed, a pin 56' being used to hold said members, which are positioned in countersunk portions of the rotor 20'. See Fig. 6.

It will also be noted that a film or fluid always surrounds the rotor at the outer ends of the spoon portions of the buckets, and also between the radius of each bucket and the corresponding radius of the rotor, insuring a high vacuum or pressure and a very efficient operation.

While I have thus described my invention with great particularity, it will be clear that the same may be modified throughout a wide range. I accordingly do not propose to be limited to the exact details of construction shown and described, but reserve the right in practice to make any and all modifications thereof that fall within the scope of the appended claims.

I claim as my invention:

1. In a rotary pump, a casing provided with inlet and discharge ports, a liner in said casing, a detachable locking key positioned in said liner and said casing and between said inlet and said discharge ports, and extending the entire longitudinal length of said casing and liner, said key being adapted to lock said liner to said casing and form also a fluid pressure seal between said inlet and said discharge ports, a rotor in said liner, and a series of fluid pressure buckets pivoted to said rotor and adapted to be actuated by centrifugal action as said rotor is rotated.

2. In a rotary pump, a casing provided with inlet and discharge ports, a rotor in said casing, said rotor being provided with a set of pockets, a fluid pressure bucket adapted to be oscillated in each of said pockets, a pivot pin forced into said rotor for each of said buckets, and means associated with said pivot pins and said rotor for maintaining said pins true.

3. In a rotary pump, a casing provided with inlet and exhaust ports, a rotor in said casing, said rotor being provided with a set of pockets, said rotor having a lip portion for each of said pockets, said lip portion providing a gap in the periphery of said rotor for each of said pockets, and a bucket mounted in each of said pockets and adapted to be swung outwardly by centrifugal force, each of said buckets having a fluid pressure actuated spoon portion adapted to be projected outwardly through said gap, each of said buckets, except said spoon portion being at all times positioned in said pockets.

4. In a rotary pump, in combination, a casing having inlet and exhaust ports, a liner

in said casing, a detachable sealing key positioned in said liner and casing between said inlet and exhaust ports, said liner having an eccentric opening, a rotor in said opening positioned concentrically with respect to said casing, said rotor being provided with a set of pockets, and a bucket mounted in each of said pockets, each of said buckets having a spoon portion adapted to be projected through a gap positioned in the periphery of said rotor and juxtaposed to each of said pockets, each of said buckets, except said spoon portion, being at all times fully enclosed within said rotor.

5. A rotor bucket adapted for use in connection with the rotor of rotary pumps, said bucket comprising a convexo-concave fluid pressure actuated spoon portion and a body portion extending from said spoon portion, said body portion being cut away to form a pivot portion for said bucket.

In testimony whereof I have signed my name to this specification.

HENRY ORR JACKSON.
